UNITED STATES PATENT OFFICE.

PAUL H. OELMAN, OF DAYTON, OHIO, ASSIGNOR TO TRADERS METAL GOODS CO., INC.,
OF NEW YORK, N. Y., A CORPORATION OF NEW YORK.

POCKET ELECTRIC LIGHT.

1,111,546.

Specification of Letters Patent. Patented Sept. 22, 1914.

Application filed August 11, 1913. Serial No. 784,076.

To all whom it may concern:

Be it known that I, PAUL H. OELMAN, a citizen of the United States, residing at Dayton, in the county of Montgomery and State of Ohio, have invented certain new and useful Improvements in Pocket Electric Lights; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 This invention relates to certain improvements in pocket electric lights.

The object of the invention is to provide a lamp or light of this type which may be carried in the upper vest pocket, and of such a size as will not interfere with the comfort or convenience of the person having such possession thereof.

My improved electric light is illustrated in the accompanying drawings of which—

25 Figures 1 and 2 are longitudinal elevations of my improved pocket light; Fig. 3 is a longitudinal sectional view; and Fig. 4 is a cross section on the line *a—a* of Fig. 3.

In a detailed description of the invention 30 similar reference characters indicate corresponding parts in the drawings.

The metallic casing or outer shell 1 is of the form of a tube or narrow cylinder suitable to be carried in the upper outer vest pocket 35 as one would carry a pencil. On the interior of said shell the battery 2 is placed with a shell of insulating material between it and the outer shell or casing. The carbon terminal 11 of the battery supports a contact member 10 which contacts with the conductor 9 of the lamp 8. The said lamp is supported in the usual socket which engages the lamp-reflector 7 placed within the mouth of the casing 1. The current through the 40 lamp is controlled by a resilient contact arm 6 one end of which is made fast to the outer end of the shell or casing 1 and the other end of which is shaped with a contact head 5 which lies over an opening 4 in the shell 45 or casing 1 and may be made to contact with the battery 2 by pressure. The resilient member 6 serves two functions; first, it is the circuit controller, and second, it provides a form of clip that receives the edge 50 of the vest pocket when the device is placed

in the pocket and thus holds said device from falling out of the pocket. The upper outside vest pocket is the most convenient pocket to carry the light in and the clip or contact 6 insures it against accidental dis- 60 placement.

I claim.

1. A pocket electric light, comprising an outer cylinder casing with an aperture in the side thereof, a battery incased in a 65 shell of non-conducting material within said casing, a lamp electrically connected with said battery, and a resilient contact arm secured to the outer cylindrical casing, said arm having its free or contact end enlarged 70 and in proximity to the aperture in said casing, and adapted to complete the circuit through the lamp and to provide means for securing the device in the pocket, substantially as described. 75

2. A pocket electric light, comprising a cylindrical casing, a battery incased in said casing, a lamp electrically connected to said battery and a resilient contact arm secured to said casing said arm having its free or contact end enlarged, said battery adapted to be placed in electrical contact with said enlarged end of said resilient arm, and said resilient contact arm adapted to complete the circuit through the lamp and to provide 85 means for securing the device in the pocket, substantially as specified.

3. A pocket electric light, comprising an outer cylindrical casing with an aperture in the side thereof, a battery incased in a shell 90 of non-conducting material within said casing, a lamp electrically connected with said battery, and a resilient contact arm secured to the outer cylindrical casing, said arm having its free or contact end in proximity to 95 the aperture in said casing, and adapted to complete the circuit through the lamp and to provide means for securing the device in the pocket, substantially as described.

4. A pocket electric light, comprising a 100 cylindrical casing, a battery incased in said casing, a lamp electrically connected to said battery and a resilient contact arm secured to said casing, said battery adapted to be placed in electrical contact with the contact end of said resilient arm, and said resilient contact arm adapted to complete the circuit through the lamp and to provide 105 means for securing the device in the pocket, substantially as specified. 110

5. A pocket flash light comprising an elongated casing having at one end a lamp and containing a battery for the lamp, and means for retaining the flash light in the pocket of the owner and closing the circuit comprising an elongated clip connected with the casing and adapted when manually operated for that purpose to close the circuit, said clip being adapted to receive between

itself and the casing the material at the front of said pocket in which the flash light may be carried.

In testimony whereof I affix my signature, in presence of two witnesses.

PAUL H. OELMAN.
